DRAW BENCH SPEED CONTROLS

Filed Feb. 23, 1932

Inventor:
CHARLES FRAZIER,
Vivian & Rauher
his Attorneys.

UNITED STATES PATENT OFFICE

CHARLES FRAZIER, OF ELLWOOD CITY, PENNSYLVANIA, ASSIGNOR TO NATIONAL TUBE COMPANY, A CORPORATION OF NEW JERSEY

DRAW-BENCH SPEED CONTROLS

Application filed February 23, 1932. Serial No. 594,623.

My invention relates to tube draw-benches. These generally include a die, a chain moving away from this die and travelling pliers constructed to engage this chain while clamping 5 the point of a tube projecting through the die, whereby the tube proper is drawn through the latter. This reduces the size of the tube because the frictional resistance offered by the metal to being pulled through 10 the die increases the pull, exerted by the pliers on the tube, to beyond its elastic limit when it becomes plastic, the tube then elongating and correspondingly decreasing in cross-section. If this distortion is suddenly 15 begun there is danger of the point on the tube being pulled off, and it is common practice to begin to draw at a slow or base speed and to afterwards increase this speed to the determined maximum drawing speed. Varying 20 the speed of the chain accomplishes this, much time being lost because it is done manually and there is a considerable lapse between the slow beginning of the draw and this speed increase.

One of my objects is to provide a machine including the above mentioned elements and having an automatic control for the chain so that elongation of a tube may be begun at a base speed which immediately increases to a 25 predetermined maximum drawing-speed. Other objects will be understood from the following disclosure.

Having reference to the accompanying drawing:

Figure 1 is a top plan of a tube draw-bench incorporating one form of my invention.

Figure 2 is a side elevation of Figure 1.

Figure 3 is a schematic drawing of the electrical circuit, and

Figure 4 is a modification of Figure 3.

The drawing shows a draw-bench 1 having a driven chain 2 that is engaged by a set of pliers 3 which themselves engage the point 45 of the tube 4 and draw it through a die 5. The operation of draw-benches of this general character is so well known that it will not be described other than this.

The pliers 3 have a depending arm 6 that 50 is fixed to a cable 7, the latter running on

sheaves 8 arranged at each end of the bench and being wrapped about a drum 9. This drum is geared to a motor 10 through a reduction unit 11. This arrangement enables the quick return of the pliers 3 from the end 55 of their stroke to starting position independently of the motion of the chain 2.

As stated, the essential feature of my invention is the control for this chain 2. To accomplish this I provide a generator 12 60 that is connected to the shaft of the motor 10 through a belt 13. The main motor 14 which drives the chain 2 is a compound wound motor with the usual series-field 15 and shunt-field 16, the latter being arranged 65 in series with a variable resistance 17. Variation of this resistance will, of course, vary the effect of the shunt-field 16, which will in turn cause the motor speed to vary. An electromagnetic switch 18 is arranged to shunt 70 the shunt-coil 16 by the resistance 17 and is connected for operation by the generator 12.

With this control it is possible to practically immediately jump the speed of the chain 2 from a slow or base speed to a predetermined 75 maximum drawing-speed. This results from the fact that the value of the resistance 17 may be adjusted so that the maximum speed of the motor is properly proportioned to drive the chain 2 at a maximum drawing- 80 speed.

The electromagnetic switch 18 will, however, effectively short-circuit this resistance so that the shunt-field coil 16 holds the motor down to draw-starting speed. Therefore, 85 when the pliers 3 are placed in engagement with the chain 2 the draw will be started at the proper speed. This motion will be practically immediately communicated 90 through the various connections described to rotate the generator 12 which will generate an operative current for the switch 18. This places the resistance 17 in effective series with the shunt-field 16, cutting down its strength and allowing the motor to pick up 95 to full tube-drawing speed.

A modification of this control may consist in having the resistance 17 shunted by a mechanical switch. This mechanical switch is generally indicated by the number 19 as op- 100

erating upon the centrifugal principle. The shaft of this switch will, of course, be belted to the shaft of the motor 10 in the same manner as the generator 12.

- 5 6 To prevent the high speed of the motor 10 being communicated to the generator 12, when driving the pliers 6 back to starting position, a ratchet clutch 20 of any suitable construction may be interposed in the belt 10 drive. This also prevents the operation of the centrifugal switch 19, if used, during this return movement.

15 Although I have shown and described a specific form of my invention in accordance with the patent statutes, I do not intend to limit myself exactly thereto, except as described by the following claims.

I claim:

- 20 1. A machine including a die, a draw-chain, tube pliers that can engage said chain, a compound-wound electric motor arranged to drive said chain, a resistance for the shunt winding of said motor, an electromagnetic switch arranged to render said resistance operable, a cable arranged to move said pliers independently of said chain, a motor ar-

25 ranged to drive said cable, and a generator connected to said electromagnetic switch and arranged for operation by movement of said cable.

2. A machine including a die, a draw-chain, 70 tube pliers that can engage said chain, a compound-wound electric motor arranged to drive said chain, a resistance for the shunt winding of said motor, a centrifugally operated switch arranged to render said resistance 75 operable, a cable arranged to move said pliers independently of said chain, a motor arranged to drive said cable, and means operable by motion of said cable to rotate said centrifugally operated switch. 80

3. A machine including a die, a draw-chain, pliers that can engage said chain, a motor arranged to drive said chain, means for varying the speed of said motor, a cable arranged to move said pliers independently 85 of said chain, a motor arranged to drive said cable and means operable by motion of said cable for controlling said first named means.

In testimony whereof, I have hereunto set my hand.

90 CHARLES FRAZIER.
